DESIGN FOR A REPRODUCTION MACHINE

Victor J. Sussin, Chicago, Ill., assignor to Litho
Equipment & Supply Company, Chicago, Ill.,
a partnership of Illinois

Application February 28, 1940, Serial No. 90,570

Term of patent 7 years

To whom it may concern:

Be it known that I, Victor J. Sussin, a citizen
of the United States, residing at Chicago, county
of Cook, and State of Illinois, have invented a
new, original, and ornamental Design for a Re-
production Machine, of which the following is a
specification, reference being had to the accom-
panying drawing, forming part thereof.

The figure is a perspective view of the repro-
duction machine, showing my design.

The opposite side of the reproduction machine
presents substantially the same appearance as
the side shown.

I claim:

The ornamental design for a reproduction ma-
chine, as shown and described.

VICTOR J. SUSSIN.
